UNITED STATES PATENT OFFICE.

BYRON K. LE CRONE, OF EFFINGHAM, ILLINOIS.

APPARATUS FOR MAKING STEREOTYPES.

1,314,275.

Specification of Letters Patent. Patented Aug. 26, 1919.

Application filed April 7, 1919. Serial No. 288,147.

To all whom it may concern:

Be it known that I, BYRON K. LE CRONE, a citizen of the United States of America, a resident of Effingham, in the county of Effingham, State of Illinois, have invented certain new and useful Improvements in Apparatus for Making Stereotypes, of which the following is a full, clear, and exact description, reference being had to the accompanying drawings, forming a part of this specification.

My invention relates to a self-contained stereotype casting apparatus having therein all of the essentials of a stereotype molding operation and so constructed as to provide for the quick and easy transfer of molten metal from a melting pot to the stereotype casting box, thereby making it possible to produce electrotypes at the maximum of speed. Furthermore, the apparatus is so constructed as to provide for instant assemblage and separation of the elements of the apparatus, so that the parts may be assembled and disassembled without the use of connecting appliances requiring time for their manipulation.

Figure I is a top plan view of my stereotype making apparatus, portions of the melting pot and casting box being shown broken out and in section.

Fig. II is a side elevation of the apparatus with the parts in the positions assumed previous to the pouring of metal.

Fig. III is a side elevation showing the parts in the positions assumed when the metal is being poured.

In the drawings, A designates a stand which may be of any suitable shape, but which preferably includes inclined rear members 1 and front members 2, connected by upwardly extending joined arms 3 provided with a keeper 4. 5 is a burner supported by the stand A, said burner being of any suitable construction for supplying heat to melt the metal used in making stereotypes.

6 designates a tilt table pivoted intermediate of its ends to the upper portion of the stand A by trunnions 7. Said table is adapted at one time to occupy a horizontal position, in which its front end rests upon a ledge 3' at the upper end of the arm 3 of the stand A, as seen in Fig. II, and at another time occupies a tilted or inclined position, as shown in Fig. III. When the tilt

table is in the horizontal position it is held from movement by a suitable latch 8, which engages the keeper 4.

9 designates a casting box, the body of which may be of any usual construction and the separable sections of which are held assembled in any ordinary manner. The casting box, which is intended to hold a matrix as usual, is provided at one of its ends with a mouthpiece 10 through which molten metal is poured to enter the box, said mouthpiece having formed thereon or secured thereto side lugs 11 of utility to be hereinafter mentioned.

12 designates a melting pot of egg shape, as shown, or of any other suitable shape. This melting pot occupies an opening in the forward portion of the tilt table 6 and is provided with a top opening through which metal to be melted may be introduced and which is normally closed by a door 13. At the rear end of the melting pot is a mouth-piece 14 with which the mouth-piece 10 on the casting box 6 registers when the casting box and melting pot are in position upon the tilt table 6.

At each side of the melting pot 12 is a side lug 15 adapted to seat within and be held by an L-shaped arm carried by the tilt table 6, the lugs 15 being located in front of the legs of said L-shaped arms, and the wings of said arms extending forwardly from said lugs, thereby preventing either rearward or upward movement of the melting pot when the lugs 15 are in engagement with the arms 16.

The melting pot 12 is also provided with rearwardly extending hook arms 18 having vertical fingers 19 spaced from each other a distance greater than the width of the mouthpiece 10 of the melting pot 9, and adapted to be engaged by the side lugs 11 carried by said mouthpiece. By engaging the side lugs 11 on the mouthpiece of the casting box with the fingers of the hook arms 18, the mouthpiece of the casting box is held in engagement with the mouthpiece of the melting pot 12, and to make such engagement firm the forward faces of the hook arm fingers 19 are inclined, as seen at 19', and the rear faces of the lugs 11 are also inclined, thereby providing a wedging action between said lugs and fingers which results in the adjustment of the smooth end

faces of the mouthpieces 10 and 14 into close contact.

The melting pot 12, in addition to being detachably connected to the tilt table 6 by the engagement of the lugs 15 with the L-arms 16 on the table, is also placed in engagement with said table by a lug 17 extending downwardly from the rearward projection of the pot which carries the hook arms 18. The melting pot is therefore engaged with the tilt table at three points, two of which prevent rearward movement of the pot on the table and the other of which holds the pot from lateral movement.

In the use of my apparatus, the melting pot is readily slipped into place on the tilt table 6 by disposing it in the opening in the forward portion of the table and moving it rearwardly, so that the side lugs 15 will become engaged with the L-arms 16 and the lug 17 will drop into the opening provided therefor in the table. The melting pot having been secured in place, a casting box having the described mouthpiece is so presented to the melting pot as to cause the side lugs of its mouthpiece to ride downwardly along the inclined forward faces of the hook arm fingers 19 until the two mouthpieces 10 and 14 are brought into registering relation and held firmly assembled to avoid leakage of metal through the joint between the mouthpieces. The operations just described are performed while the tilt table is in the horizontal position shown in Figs. I and II. Assuming now that molten metal, heated by the use of the burner 5, is present in the melting pot, the next act of the operator is to release the latch 8 and tilt the table 6 from the horizontal position to the inclined position shown in Fig. III. By so tilting the table the melting pot and the casting box supported thereon are placed in inclined position, the molten metal passing from the pot to the box through the mouth pieces 14 and 10, with resultant casting operation. The tilt table is then returned to a horizontal position prior to the separation of the casting box from the melting pot. To permit the ready separation of the casting box from the melting pot the lower portions of the lugs 11, carried by the mouthpiece of the casting box, are rounded or cut away, as seen at 11^a, so that the rear edges of these portions of the lugs are separated from the opposing portions of the hook arm fingers 19 engaged by the remaining portions of the lugs. These cut away portions of the lugs 11 enable the operator to tilt the casting box upwardly in separating its mouthpiece from the mouthpiece of the melting pot, and by so tilting the casting box the sprue extending through the mouthpieces is broken, so that the casting box is readily separated from the melting pot.

It will be apparent that various sized

casting boxes may be employed in the use of my apparatus, it being essential only that the mouth piece of the box, irrespective of the size of the box, be of a size and shape to fit the mouth piece of the melting pot.

70

I claim:

1. An apparatus of the character described, comprising a tiltable support, a melting pot arranged on said support, said melting pot having a mouthpiece, and a casting box having a mouthpiece, one of said parts having hook arms and the other having elements for engagement with said hook arms whereby the parts are connected to each other to hold said mouthpieces in mating relation.

75

2. An apparatus of the character described, comprising a tiltable support, a melting pot arranged on said support, said melting pot having a mouthpiece, and a casting box having a mouthpiece, said melting pot being provided with hook arms and said casting box being provided with lugs for engagement with said hook arms, whereby said mouthpieces are held in mating relation.

80

3. An apparatus of the character described, comprising a tiltable support, a melting pot arranged on said support, said melting pot having a mouthpiece, and a casting box having a mouthpiece, one of said parts being provided with tapered hook arms and the other with tapered lugs, for engagement with each other to hold the mouthpieces in mating relation.

85

4. An apparatus of the character described, comprising a tiltable support, a melting pot arranged on said support, said melting pot having a mouthpiece, and a casting box having a mouthpiece, one of said parts being provided with tapered hook arms and the other with tapered lugs, for engagement with said hook arms whereby the mouthpieces of the parts are held in mating relation, said lugs being partially cut away to permit the separation of the mouthpieces when a casting has been formed in the casting box.

90

5. An apparatus of the character described, comprising a tiltable support, a melting pot detachably mounted on said support, and a casting box detachably connected to said melting pot, said melting pot and casting box having detachable mating mouthpieces.

95

6. An apparatus of the character described, comprising a tiltable support, a melting pot detachably mounted on said support and having means for engagement therewith serving to hold the melting pot from longitudinal and lateral movement relative to the support, and a casting box detachably connected to said melting pot, said melting pot and casting box having separable mating mouthpieces.

100

105

110

115

120

125

130

7. An apparatus of the character described, comprising a tiltable support having socket arms, a melting pot having side lugs for detachable engagement with said 5 socket arms, and being provided with a mouthpiece, and a casting box having a mouthpiece for mating relation with the mouthpiece of said melting pot, the melting pot and casting box being provided with interengaging means whereby their mouth- 10 pieces are separably joined to each other.

In testimony that I claim the foregoing I hereunto affix my signature.

BYRON K. LE CRONE.
